Res. 140

J. Gross & Son Ass'ts of S. W. Gibbs Albany, N.Y.
Letters Patent No 240 dated Oct. 9, 1840.

The schedule referred to in these letters patent and making part of the same.

To all whom it may concern: Be it Known that I, James W. Gibbs, of the City of Albany, and State of New York, have produced a new ornamental design for an airtight Parlour Stove, and I do declare that the summary and accompanying drawings with the explanations attached to the same, give a full and accurate description of my said ornamental design.

What I claim as my production & ask to have secured to me by letters patent is the combination and

D
arrangements of Ornamental figures and furniture presented in the accompanying drawings making an Ornamental Design for a parlour Stove.
